UNITED STATES PATENT OFFICE

2,102,714

DOOR HANDLE MOUNTING

Gerald V. Jakeway, Grand Rapids, Mich., assignor to Keeler Brass Company, Grand Rapids, Mich.

Application September 5, 1936, Serial No. 99,565

16 Claims. (CL 292—350)

The main objects of my invention are:

First, to provide a novel and improved mounting for an automobile door handle.

Second, to provide a mounting of the type described which is economical in construction and highly pleasing in appearance.

Third, to provide a mounting of the type described which eliminates the necessity for the conventional exterior escutcheon securing screws, hence improves the appearance of the mounting and prevents unauthorized removal thereof.

Fourth, to provide a mounting of the type described which is simple in its parts and readily assembled on an automobile, or other, door to which it is applied.

Further objects relating to details and economies of my invention will definitely appear from the description to follow. The invention is defined in the claims. Preferred embodiments of the invention are illustrated in the accompanying drawing, wherein:

Fig. 1 is a fragmentary view partially broken away and in section on line 1—1 of Fig. 4, illustrating the door handle mounting in assembled position on an automobile door.

Fig. 2 is an enlarged fragmentary sectional view on line 2—2 of Fig. 3.

Fig. 3 is a fragmentary view in section on line 3—3 of Fig. 2, illustrating details of the securing means in one form.

Fig. 4 is a fragmentary view in vertical section on line 4—4 of Fig. 1, illustrating details of my device.

Fig. 5 is a fragmentary view in horizontal section illustrating the manner in which my device is assembled on a door, a modified form of securing means being shown in this view.

Outside door handle mountings for automobiles ordinarily employ escutcheon plates provided with exposed screws whereby the same are fastened to the door. In addition to the fact that screw holes and screws therein needlessly detract from the appearance of the mounting, the accessibility of the screws renders it easy to tamper with or remove the mounting. I have devised a door handle mounting comprising an escutcheon member which is free from both of the above named disadvantages and which is exceedingly simple in construction. Broadly considered, the invention resides in securing a plain escutcheon to a door by means of a threaded member inserted in the door from the edge thereof normally adjacent the frame, whereby in closed and locked position the securing means is hidden and

enclosed between the door and door frame and is, hence, inaccessible for tampering.

Referring to the drawing, reference numeral 1 generally indicates a door in closed relation to its frame 2, the door being provided with an overhanging lip 3 adapted to seat against a land 4 on the frame to seal the door and prevent access to the securing means, to be hereinafter described, in closed position of the door. The outer door panel 5 is conformed to provide lip 3 in a well known manner and likewise is apertured at 6 to receive the handle escutcheon member 9, a reinforcing plate 7 being welded to the inside of the panel at 8 and apertured in line with opening 6. Plate 7 consists of a one-eighth inch reinforcing plate approximately two and one-half inches wide and has an offset or locking member 70 struck out from one end thereof, the offset being provided with a hole 71 for a purpose to be hereafter described.

Escutcheon member 9 fits snugly within opening 6 and has a cylindrical wall 10 provided with an integral lug 11 engaging a notch 12 in panel 5 for the purpose of locating and preventing turning of the escutcheon relative to the door. The escutcheon member has a tapered portion 13 provided with an internally threaded sleeve 14 suitably secured therein and in alignment with hole 71 for the purpose of receiving locking screw 15. Sleeve 14 carries integral lugs 18 cooperating with corresponding notches in the hole in which it is mounted, as illustrated in Fig. 3, to prevent rotation of the sleeve therein.

On the outer edge 16 of the door, I form an opening 17 whereby screw 15 may be inserted during assembly, the screw extending through hole 71 in offset 70 and threadedly engaging sleeve 14. Thus in assembled position, with the annular flange 19 of the escutcheon member abutting door panel 5 and with lug 11 engaged in the locating notch 12, the screw 15 may be advanced to engage the escutcheon member and draw the same firmly against the door panel.

Specific details of the handle construction, such as handle member 20, spindle 21, and tensioning spring 22, form no part of my present invention and will not be described at length.

Fig. 5 illustrates a modified form of my invention, as well as the manner of assembling the elements in located position, the embodiment of Fig. 5 employing a circular boss 23 drilled and tapped to receive screw 15 which extends through a hole 24 formed in a recess 25 upset in the edge of the door adjacent the frame, the recess hole, hole 71, and threaded boss being in alignment.

Screw 15 passes through the hole 71 and threadedly engages the escutcheon in the same manner described relative to the modification of Fig. 1. In other respects the mountings are identical and need not be further described.

From the above description, the advantages of my device will be clear. By the use of a blind fastening instead of an escutcheon plate having exposed screws, the handle mounting is rendered 10 tamper proof and the appearance of the same is materially improved. Use of the construction of my invention entails little modification of existing door structures and the assembly of the fastening means on the door may be easily and 15 quickly performed.

I have illustrated and described my improvements in an embodiment which I have found very practical. I have not attempted to illustrate or 20 describe other embodiments or adaptations as it is believed this disclosure will enable those skilled in the art to embody or adapt my improvements as may be desired.

Having thus described my invention, what I claim as new and desire to secure by Letters 25 Patent is:

1. In a handle mounting for an automobile door panel apertured to receive the same, a reinforcing plate secured to said panel and apertured in line with the panel aperture, said plate having a locking offset, an escutcheon member fitted in said apertures and having an annular flange abutting said panel, the door having an opening in the edge thereof adjacent the frame, said locking offset having a hole therein and said 30 escutcheon member having a threaded element in alignment with said hole and opening, and a screw abutting said offset and extending through said hole in threaded engagement with said element and operative to secure said escutcheon 35 member on said door.

2. In a handle mounting, a reinforcing plate apertured to receive an escutcheon member, said plate having an offset locking portion provided with a hole, said escutcheon member having a hole in alignment with said first named hole, and means extending through said holes and operative to secure said escutcheon member on said door, said door having an opening in the edge thereof adjacent the frame to permit assembly 50 of the mounting.

3. In a door handle mounting, in combination, an inner reinforcing plate, said plate having an aperture, an escutcheon member fitted in said aperture and having an annular door abutting flange, and a screw abutting said plate and extending from the edge of the door into locking engagement with said escutcheon member and operative to secure said escutcheon member on said door.

4. In a door handle mounting, in combination, an escutcheon member adapted to be fitted in an aperture in a door and having an annular door abutting flange, and threaded means extending from the edge of the door toward the 65 outer side thereof into engagement with said escutcheon member and operative to secure said escutcheon member on said door.

5. In a door handle mounting, in combination, an escutcheon member adapted to be fitted in an aperture in a door and having an annular door abutting flange, and tensioning and locking means extending from the edge of the door toward the outer side thereof into engagement with said escutcheon member and operative to secure said escutcheon member on said door.

6. In combination with a door, a door handle escutcheon and means to mount said escutcheon on the door comprising a threaded sleeve carried by said escutcheon, a screw threadedly engaged with said sleeve, said door having an opening in its edge receiving said screw, a member carried by the door against which said screw abuts, said screw extending angularly toward the outer side of the door and threadedly engaging the sleeve and being adapted to draw and secure the escutcheon to the door.

7. In combination with a door, a door handle escutcheon and means to mount said escutcheon on the door comprising a screw threadedly engaged with said escutcheon, said door having an aperture in its edge receiving said screw, said screw extending toward the outer side of the door and engaging the escutcheon and being adapted to draw and secure the escutcheon to the door.

8. A door handle escutcheon and means to mount the same on a door, comprising a screw extending from the edge of the door toward the outer side thereof, said escutcheon having a threaded hole engaged by said screw whereby the escutcheon may be drawn against the door, said escutcheon having an annular flange adapted to seat tightly against the outer door panel in mounted position of the escutcheon, said screw drawing said escutcheon toward said outer door panel.

9. A door handle escutcheon and means to mount the same on a door, comprising a screw extending from the edge of the door toward the outer side thereof, said escutcheon having a threaded hole with the axis thereof disposed at an angle to the axis of the escutcheon, said hole being engaged by said screw whereby the escutcheon may be drawn against the door.

10. In combination with a door, a door handle escutcheon and means to mount said escutcheon on the door comprising means extending angularly toward the outer side of the door from the edge thereof and engaging the escutcheon angularly relative to the axis of said handle and escutcheon, said engaging means being adapted to draw and secure the escutcheon to the door.

11. A door handle escutcheon and entirely-concealed means to mount the same on a door comprising a screw extending from the edge of the door adjacent the door frame toward the outer side of the door, said escutcheon carrying a threaded hole engaged by said screw whereby the escutcheon may be drawn against the door, said escutcheon having means integral therewith to locate and prevent its rotation in the door, and an annular flange adapted to seat tightly against the outer side of the door in mounted position of the escutcheon.

12. A door handle escutcheon and entirely-concealed means to mount the same on a door comprising threaded means extending from the edge of the door adjacent the door frame toward the outer side of the door, said escutcheon being engaged by said means whereby the escutcheon may be drawn against the door, said escutcheon having means integral therewith to locate and prevent its rotation in the door, and an annular flange adapted to seat tightly against the outer side of the door in mounted position of the escutcheon.

13. A door handle escutcheon and entirely-concealed means to mount the same on a door comprising threaded means extending angularly from the edge of the door adjacent the door

frame toward the outer side of the door, and means engaged by said angularly extending means whereby the escutcheon may be drawn against the door.

5. 14. In a door handle mounting, in combination, an escutcheon member fitted in an aperture in a door, said door having a recess offset in the edge thereof adjacent the frame, said escutcheon member having an internally threaded portion in 10 alignment with said recess, and means engaging said recess and threaded portion to secure said escutcheon member on said door.

15. 15. In a door handle mounting for a door having a hole in the edge thereof adjacent the door frame, an escutcheon member fitted in an outer opening in the door, said escutcheon member having a hole in alignment with said door hole,

securing means mounted in said escutcheon member adjacent the hole area, and means extending through the door hole toward the outer side of the door and engaging said securing means whereby the escutcheon member is secured in operative position on the door. 5

16. In a door handle mounting for a door having a hole in the edge thereof adjacent the door frame, an escutcheon member fitted in an outer opening in the door, securing means on said 10 escutcheon member adjacent the hole area, and screw means extending through the door hole toward the outer side of the door and engaging said securing means whereby the escutcheon member is secured in operative position on the 15 door.

GERALD V. JAKEWAY.
